ATTORNEY.

UNITED STATES PATENT OFFICE.

EDWIN A. KINNE, OF KANSAS CITY, MISSOURI.

HITCHING-POST.

SPECIFICATION forming part of Letters Patent No. 373,832, dated November 29, 1887.

Application filed April 28, 1887. Serial No. 236,436. (No model.)

To all whom it may concern:

Be it known that I, EDWIN A. KINNE, of Kansas City, Jackson county, State of Missouri, have invented a new and Improved 5 Hitching-Post, of which the following is a full, clear, and exact description, reference being had to the accompanying drawings, forming a part hereof.

The object of my invention is to provide a 10 hitching-post that can be lowered into a receptacle located below the surface of the ground when not in use, and that can be withdrawn therefrom and secured thereto in position at the proper height when desired for 15 use.

My invention consists in the devices and combination and arrangement of devices hereinafter set forth, and pointed out in the claim.

In the drawings which illustrate the manner of carrying out the invention, Figure 1 is a perspective view of the post as it appears in position for hitching animals thereto; and Fig. 2 is a sectional elevation showing the box or casing located in the ground.

25 A indicates the post, which may be either rectangular or circular in cross-section, or of any suitable form, and constructed of any desired material, and which can be lowered into the box or casing B when not in use, as shown.

30 The casing B is preferably constructed of cast-iron, with a flange, B', at its upper end, by means of which it will be prevented from sinking too deep in the ground, and which can be provided with screw or bolt holes for

35 securing the casing to the pavement, when located on a pavement, as indicated. Said casing is also provided on the inside, near the top thereof, with a notch or depression, E', the shoulder of which is to be engaged by a pawl,

40 E, on the lower portion of the post to keep said post from being withdrawn too far during use.

The pawl E is pivoted at a' in a recess, D, formed in the lower portion of post A, and it 45 is provided with a weighted free end and caused to engage said depression by the action of gravity, as shown.

For the purpose of holding the post A at any desired height in relation to the casing B, I locate another pawl, C, in a suitable cavity 50 or recess, C', formed in the body of the post, and cause one end of said pawl (indicated by letter a'') to automatically engage the upper end of the casing when the post is withdrawn and adjusted to position.

55 The post is prevented from falling too low in the casing by means of a cap or flange, b, which is formed upon or secured to its upper end, and which is adapted to rest upon the flange B' of the casing when the post is not in use. A hitching-ring, d, or any similar device, is secured to the upper end of the post, by means of which it may be withdrawn from the casing.

60 It is obvious that a post constructed as indicated can be used for various purposes—such, for instance, as supporting the wires of fences and the like.

65 The operation of the invention is as follows: When the post is to be withdrawn from the casing, the operator lifts it upward the required distance, until the pawl C engages the upper end of the casing, when it will be held in a withdrawn position until said pawl is disengaged, which can be accomplished by the 70 operator's foot, as will be readily seen.

75 I do not herein broadly claim a hitching-post capable of being raised and lowered in a receptacle located in the ground; but

80 What I claim is—

In a hitching-post, the combination, with the casing B, having the flange B' at its upper end and the notch or depression E' on its inside, near the top thereof, of the post A, having the slots C' D in the central and lower 85 portion thereof, respectively, and pawls C and E, pivoted within said slots, substantially as described.

In testimony whereof I affix my signature in presence of two witnesses.

EDWIN A. KINNE.

Witnesses:

ALBERT SAVAGE,
A. A. HIGDON.
